LIGHTING FIXTURE GLOBE

Howard A. Daum, Pittsburgh, Pa.

Application April 24, 1956, Serial No. 41,188

Term of patent 14 years

(Cl. D48—16)

Fig. 1

Fig. 2

Figure 1 is a top plan view of a lighting fixture globe showing my new design; and

Figure 2 is a side elevational view thereof.

I claim:

The ornamental design for a lighting fixture globe, as shown.
